UNITED STATES PATENT OFFICE.

WILLIAM B. CAMPBELL, OF NASHVILLE, TENNESSEE.

DESIGN FOR A SMOKER'S SET.

Application filed September 2, 1927. Serial No. 23,283. Term of patent 7 years.

To all whom it may concern:

Be it known that I, WILLIAM B. CAMPBELL, a citizen of the United States, residing at Nashville, in the county of Davidson and State of Tennessee, have invented a new, original, and ornamental Design for a Smoker's Set, of which the following is a specification, reference being had to the accompanying drawing, forming part thereof.

The figure is a view in perspective of a smoker's set, showing my new design.

I claim:

The ornamental design for a smoker's set, as shown.

WILLIAM B. CAMPBELL.
